TRIPLE FESTOON VALANCE
Sam Shapiro, Forest Hills, N.Y.
(261 5th Ave., New York 16, N.Y.)
Filed Apr. 4, 1963, Ser. No. 270,677
1 Claim. (Cl. 160—124)

This invention concerns both a novel valance with triple festoons and a method of manufacturing the valance.

According to the invention the valance is made of three cloth quadrants joined together in such a manner that they fall naturally in graceful folds when hung on a conventional curtain or drapery rod. Two, three or more valances embodying the invention can be hung on a single rod to extend across windows of double, triple or greater width. A single valance having three festoons will extend across a single window when hung on a single rod.

It is a principal object of the invention to provide a novel valance construction.

It is another object of the invention to provide a valance having three generally semi-oval festoons formed by overlapping folded circular quadrants of fabric.

A further object is to provide a novel method of fabricating a valance having triple festoons made of folded circular quadrants of fabric.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

FIG. 1 is a front elevational view of a triple festoon valance embodying the invention.

FIG. 2 is a front elevational view of a single valance and two drapes arranged for dressing a window of single width.

FIG. 3 is a front elevational view of two valances and two drapes arranged for dressing a window of double width.

FIG. 4 is a plan view of a length of fabric laid out for cutting into festoon parts in a first step of fabricating a triple festoon valance.

FIG. 5 is an exploded plan view of parts of a triple festoon valance.

FIGS. 6A-6G are plan views of a valance shown in successive steps of fabrication.

FIG. 7 is a sectional view on an enlarged scale taken on line 7—7 of FIG. 6B.

FIGS. 8 and 9 are sectional views on an enlarged scale taken on lines 8—8 and 9—9, respectively, of FIG. 6G.

Referring first to FIG. 1, there is shown a valance 10 consisting of three festoons 12A, 12A' and 12A'' secured by stitching 14 to a fabric tube 16 which provides a passage for engaging a round or flat supporting rod 18 extending axially through the tube. Fringed trimmings 19 are secured to the free curved edges of the festoons.

The valance 10 is formed from parts shown to best advantage in FIG. 5. These parts include an elongated rectangular fabric strip or band 16a which is used to form the tube 16. Three festoon parts A, A' and A'' are each originally in the form of flat, unfolded circular quadrants. Each part has a circular curved edge 20 which extends through 90° of arc, and two intersecting straight edges 22 and 24 which extend perpendicularly to each other radially of the quadrant. The apex or corner of the quadrant has a square notch 25 with mutually perpendicular edges 26 and 28 respectively parallel to edges 22, 24. Edge 26 extends perpendicularly to edge 24 and inwardly therefrom, while edge 28 extends perpendicularly to edge 22 and inwardly therefrom. Fringed trimming strips 19 are

2

provided for attachment to the curved edges 20 of the several quadrants.

While the festoons can be made in various sizes, fabrication will be described in connection with a preferred size made from a bolt of cloth 32 having a width of forty-four inches as indicated in FIG. 4. This cloth may have any desired length. A plurality of layers of cloth can be superimposed for cutting simultaneously into festoon parts. The cloth can be cut along transverse lines L1 spaced twenty-two inches apart. The cloth will also be cut along a central line L2 to form squares S with lines L1. Each square is twenty-two inches on a side. Each square of cloth will be cut along a circularly curved line 20 of 90°. Line 20 has a radius of curvature equal to one half of line L1 or twenty-two inches. Square holes H, which are about two and one-half inches on each edge, will be cut at the intersections of lines L1 and L2 to form square notches 25. Two festoon parts defined between curved lines 20 and straight line parts L1, L2 are thus formed between each two transverse lines L1, L2. The straight edges of the festoon quadrants are each about twenty and three-quarters inches in length while the edges of the notches are each about one and one-quarter inches in length.

After the cloth 32 is cut up into flat circular quadrants, three of these parts A, A', A'' are employed to assemble the valance by following steps indicated in FIGS. 6A-6G. Initially a fringed trimming strip 19 is secured by stitching 34 to the curved edge of each festoon quadrant to form festoons 12A, 12A', 12A''. A first flat festoon quadrant 12A is disposed as shown in FIG. 6A with edge 22 overlapping one edge 23 of strip 16a at the left end of the strip. Then edge 22 is sewn to edge 23 by stitching 33 extending about eighteen inches from the trimming strip 19 to a point about an inch from the edge 28 of notch 25. The festoon quadrant 12A is then folded along radial and circumferential lines and edge 24 is brought up into alignment with edge 22 and overlapping edge 23 of strip 16a. The edge 26 of notch 25 will then be disposed perpendicular to the aligned edges 22 and 24 in abutting engagement with the edge 28 thereof as viewed in FIG. 6B. The outer corners C1, C2 of the notch thus overlap each other with corner C1 above corner C2; see FIG. 7.

Then a second festoon 24A' is disposed in overlapping position on festoon 12A with edge 22 of festoon 12A' registering with edge 24 of festoon 12A. Stitching 36 indicated in FIG. 6C then is applied to secure edge 24 of festoon 12A and edge 22 of festoon 12A' to the lower edge 23 of strip 16a. Stitching 36 is stopped about an inch from notch 25 of festoon 12A'.

In the next step indicated in FIG. 6D, the third festoon 12A'' is disposed adjacent to festoon 12A' with edge 22 of festoon 12A'' overlapping the strip 16a and in alignment with edge 22 of festoon 12A'.

Festoon 12A' is then folded on radial and circumferential lines so that edge 24 of festoon 12A' overlaps edge 22 of festoon 12A'' as indicated in FIG. 6E. The edge 26 of the notch in festoon 12A' abuts the edge 28 of the notch. Then stitching 38 is applied to secure edge 24 of festoon 12A' and edge 22 of festoon 12A'' to strip 16a. The stitching stops about an inch from notch 25 of festoon 12A'' which is now under festoon 12A'; see FIG. 8.

Festoon 12A'' is then folded on radial and circumferential lines to bring edge 24 up to the strip 16a in alignment with edge 24 of festoon 12A' as indicated in FIG. 6F. Stitching 40 is applied to secure edge 24 of festoon 12A'' to the strip 16a. Then ends 42A, 42B of strip 16a, which extends outwardly beyond festoons 12A and 12A'', are folded inwardly and stitched at 44 to conceal raw edges of the strip.

The strip 16^a is next folded down on fold line F1 indicated in FIGS. 6F and 6G to form tube 16 which receives curtain rod 18; see FIG. 9. Stitching 46 is applied through the folded down edge 23' of strip 16^a and serves as a reinforcement of stitching 36, 38 and 40 previously applied at the edges of the festoons. The straight edges of the festoons are all disposed in alignment or in overlapping registration with each other and between facing edges 23, 23' of the looped, tubular strip or band 16.

The assembly of festoons and rod receiving tube forms a single valance 10 as indicated in FIGS. 1 and 6G. By employing another curtain or drapery rod behind the valance; two drapes 45A, 45B can be associated with the valance 10 to define a drape and valance treatment for a window of single width as indicated in FIG. 2. Tie backs 48 made of the same fringed strip material as festoon trimmings 19 can be supplied for tying back and hanging the drapes in graceful folds.

FIG. 3 shows two valances 10' and 10" each identical in construction with valance 10 mounted on a single rod 18'. Drape 45' is located behind festoon 12A of valance 10' and drape 45" is located behind festoon 12A" of valance 10". Both drapes are mounted on a second rod (not shown) located behind the valances. Tie backs 48', 48" are applied to the drapes. This assembly provides a treatment for a window of double width. Obviously three or more valances could be mounted on a single rod for treating still wider windows.

In all cases, each valance has a triple festoon assembly in which the individual festoons naturally fall into graceful radial and circumferential folds when the valance is hung on a rod. A minimum of hand dressing is required. The several festoons all have generally semi-oval configurations. The longer or major axis of each oval is located at edges 23, 23' of the tubular band 16. This is a geometrically correct and aesthetically very attractive arrangement.

It will be noted that each semi-oval festoon is made by folding a flat circular quadrant of cloth. The apical notch 25 facilitates proper folding of the quadrant and aligning of the straight edges to form a draped, folded oval.

There has thus been described and illustrated both a novel valance with triple semi-oval festoons and a novel method of fabricating the valance. The valance can be made of different kinds of fabric and in different lengths and widths as desired. The fringed trimming 19 can be omitted or different types of trimming can be applied.

While I have illustrated and described the preferred embodiment of my invention, it is to be understood that I do not limit myself to the precise construction herein disclosed and that various changes and modifications may be made within the scope of the invention as defined in the appended claim.

Having thus described my invention, what I claim as new, and desire to secure by United States Letters Patent is:

- 10 A valance for dressing a window, comprising an elongated strip folded along a longitudinal line to define a tube for receiving a drapery rod therethrough, and three draped, folded festoons secured between facing edges of the folded strip, each of said festoons being formed from a flat circular quadrant of material, each flat quadrant having two straight radial edges terminating at one end in a rectangular notch and at the other end at opposite ends of a circularly curved edge, the two straight edges of each folded festoon being disposed in alignment between the edges of the folded strip, with the remainder of the festoon defining a generally semi-oval body, and with edges of the notch disposed perpendicular to the aligned straight edges in abutting engagement with each other, two of the folded festoons being disposed in a coplanar arrangement with one end of the curved edge of one of the two festoons disposed adjacent to an end of the curved edge of the other one of the two festoons, and with the third festoon centered on said strip and overlapping parts of both of said two festoons while other parts of the two festoons are free from the third festoon.
